FAUCET

Frank E. Rice, deceased, late of Detroit, Mich., by
Nelson E. Rice, administrator, Detroit, Mich.

Original application October 4, 1940, Serial No.
359,661, now Patent No. 2,331,729, dated Octo-
ber 12, 1943. Divided and this application
February 13, 1942, Serial No. 430,752

2 Claims. (Cl. 251—132)

This application is a division of the co-pending application entitled "Direct draw faucet assembly," filed October 4, 1940, United States Serial No. 359,661, now Patent No. 2,331,729, granted October 12, 1943.

This invention relates to a beverage dispenser and more particularly to a beer faucet arranged and constructed for cooperation with a draw rod assembly for together insulating, from room temperatures, a small volume of beer trapped therein during periods of inactivity as described in the above-mentioned co-pending application.

At the present time, great difficulty is experienced in providing faucets for carbonated beverages which will assure the drawing of a single glass of the beverage at the proper temperature and carbonation after the faucet has remained idle and has been exposed to room temperatures for a period of time. This is particularly true when the beverage is beer. During warm weather, even an idle period of fifteen minutes will result in the first glass of beer being unsalable due to excess foam and increased temperature of the liquid. As the solubility of carbon dioxide gas decreases as the temperature increases, the beer contained in such a faucet will lose much of its carbonation and the free gas will form pockets which cause spitting or sudden bursts of liquid when the faucet is opened, with the result that excess foam is formed as the beer is being drawn.

While this problem may be solved satisfactorily by refrigerating or cooling the casing of the faucet, the results are unsatisfactory due to the increased manufacturing costs and complications in fabrication of this type of faucet.

It is, therefore, an important object of the present invention to eliminate these objections by providing an inexpensive and unrefrigerated faucet assembly.

Another object of this invention is to provide a faucet so constructed as to hold a very small volume of beverage therein during periods of inactivity.

A still further object of this invention is to provide a faucet constructed to cooperate with a refrigerated draw rod assembly whereby a small volume of beverage, trapped therein during periods of inactivity, is maintained at substantially the same temperature as in the refrigerated source from which the beverage is drawn.

Another and still further object of this invention is to provide a faucet adapted to be coupled to a refrigerated draw rod assembly and having a valve member extending into the draw rod

assembly for defining a refrigerated flow continuation therefrom.

A still further object of this invention is the provision of a faucet adapted to be coupled to a refrigerated draw rod assembly which effects the drawing, from a refrigerated source of supply, of a salable glass of beer having the proper amount of foam and the proper carbonation and temperature even after the faucet has remained out of operation for long periods of time in relatively high room temperatures.

A further object of this invention is the provision of a faucet having a novel handle and valve construction which cooperate with cam action.

Another and still further object of this invention is the provision of a faucet having a handle and valve construction in which the handle is automatically returned to a valve-closed position when operated partially between its operating limits and which may be actuated to a full valve-opened position and retained in that position until manually returned partway when the faucet is again automatically closed.

The novel features believed to be characteristic of the present invention are set forth with particularity in the appended claims. The invention itself, however, both as to its organization and manner of construction, together with further objects and advantages thereof, may best be understood by reference to the following description taken in connection with the accompanying drawing, in which:

Figure 1 is an elevational view, as seen from one side, of a faucet connected to a refrigerated draught tube assembly in accordance with the principles of this invention;

Figure 2 is an enlarged broken vertical cross-sectional view showing details of construction of the faucet in connection with a draught tube assembly as shown in Figure 1;

Figure 3 is an enlarged transverse cross-sectional view taken substantially along the plane indicated by the line III—III of Figure 2; and,

Figure 4 is an enlarged fragmentary cross-sectional view of the valve head assembly illustrated in Figure 2.

The assembly device illustrated in Figure 1 generally comprises a faucet construction 10 and a connected draught tube assembly 11. A portion 12 of a refrigerating box or container is illustrated only for the purpose of showing the faucet construction 10 and a portion of the draught tube assembly 11 as being exposed to room temperatures. The connection between the

assembly illustrated and the refrigerating cabinet forms no part of this invention and therefore will not be described. A line 13—13 represents the general position of the top of a beer barrel through which the draught rod 11 is inserted. No connection for the draught rod with a beer barrel is shown as it forms no part of this invention.

As best shown in the enlarged broken sectional view in Figure 2, there is illustrated a tubular shell 14 lined on its inner side with cork 15 or other suitable insulating material. At the upper end of the shell there is provided a closure cap 16 having a lower portion 17 of reduced diameter for abutment insertion within the shell. While no insulating material has been shown for lining the cap 16, cork or other suitable and similar insulation may be used if desired. A spacer bushing 18 is inserted within the lower end of the shell 14 with its outer face in flush relation with the lower edge of the shell. This bushing is provided with a peripheral wall 19 for engagement with the inner surface of the shell 14 and a central apertured bushing 20 for receiving therethrough the draught tube 11. The bushing 20 is connected to the peripheral wall 19 by means of a plurality of ribs or spiders 21. As the side walls of the draught tube 11 are too thin to permit the draught tube to be pressed through the central aperture of the bushing 20, the draught tube is connected to the bushing by solder or other suitable means.

The upper end of the draught tube 11 is threaded for connection to an internally threaded elbow member 22. As shown, the elbow 22 is provided with a downwardly extending leg 23 which is internally threaded as at 24 for connection to the draught tube. A shorter leg 25 is disposed in angular relation to the leg 23 for a purpose to be more fully described hereinafter. The side walls of the elbow 22 are apertured as at 22a to allow for air circulation through the elbow and downwardly within the draught tube 11. The top wall 26 of the elbow 22 is thickened and provided with a threaded recess into which is inserted a cap screw 27 for the purpose of aiding in the support of the elbow by the cap 16. It is to be noted that the connection between the bushing 18 and the draught tube 11 together with the connection between the cap screw 27 and the elbow 22 provides an axial support for the operative structure of the draught rod and faucet assembly.

A nozzle assembly 28 is formed as a union with a female coupling portion at one end formed by a coupling sleeve 29 and an internally threaded coupling nut 30. The sleeve 29 is provided at one end with a reduced portion 31 which is pressed into the short hollow leg 25 of the elbow member 22. If desired, this connection can be made more positive by soldering, welding, threading or the like. An outwardly extending flange 32 is provided adjacent the opposite end of the coupling sleeve against which the inner shoulder of the loosely swiveled coupling nut 30 abuts when threadedly connected to the nozzle proper 33. The outer surface of the coupling nut 30 is knurled as shown in Figure 1, to provide a rough surface for aiding in turning the nut by hand when the parts are connected together.

The nozzle 33 forms the male portion of the union nozzle assembly 28. One end of the nozzle 33 is provided with exterior threads for engagement with the interior threads of the coupling nut 30 whereby a tightening of the coupling

nut draws the end of the nozzle 33 into abutment with the outer face of the flange 32. In order that the coupling sleeve 29 and the nozzle proper 33 be connected in proper alignment so that the nozzle outlet faces downwardly as shown in Figures 1 and 2, a slot 32a is provided in the flange 32 of the sleeve 29 for receiving therein a forwardly extending lug 33a on the threaded end of the nozzle 33.

A recess 34 is provided at the threaded end of the nozzle 33 for receiving therein an end of the sleeve 29, and a sealing washer 35 is interposed between the end of the sleeve 29 and the shoulder formed at the end of the recess 34 to provide a fluid-tight joint when the union parts comprising the faucet assembly 28 are connected together.

At an intermediate inner portion of the nozzle 33, there is provided a reduced passageway 36 forming a valve seat 37. Between the valve seat 37 and the recess 34 there is formed an enlarged valve chamber 38 whose purpose is to be described more fully hereinafter.

The reduced chamber 36 is continued in two angularly extending branches, one of which extends in an axial direction as a reduced guide cylinder 39 and the other continued in an angular direction therefrom as a nozzle opening 40 which is formed by the tap or spigot 41.

The outwardly extending end of the nozzle 33 terminates in a portion of U-shaped configuration in cross section having a web 42 and spaced parallel side walls 43, only one of which is shown in Figure 2.

A handle member 44 is provided at one end 35 with a cam portion 45 which is pivotally connected to and between the side walls 43 by means of a screw or pivot pin 46. Substantially right-angularly extending cam surfaces 47 and 48 are provided respectively at the end and top edge of the cam portion 45 to form a slightly rounded corner 45a therebetween. When the pivoted handle 44 is rocked to the position illustrated in Figure 2, the cam surface 48 moves into engagement with the offset inner surface 49 of the web portion 42. A shoulder 50 is provided thereby for engaging a portion of the cam surface 47.

A ball handle or grip 51 is formed at the end of the member 44 opposite the cam end in order that the handle may be grasped and rocked about its pivot 46. The handle 51 may be formed of any suitable material and it is preferred that it be formed of a suitable colored plastic which contrasts with the metal finish of the faucet assembly.

A fluid tube 52, of smaller diameter than the inside diameter of the draught tube 11, has one end inserted within a portion of the end 31 of the coupling sleeve 29. The inserted end is flared slightly outwardly as at 53 to eliminate the possibility of the tube 52 being pulled out of engagement from within the sleeve 29. The tube 52 is then bent angularly downward to pass through the elbow member 22 and a portion of the draught tube 11 in coaxial alignment therewith. A bushing 54 is sweat into place or otherwise suitably secured to the inner surface of the side walls of the draught rod 11 to tightly embrace a portion of the lower end of the fluid tube 52. This connection provides a fluid-tight joint between the tubes 11 and 52 and, together with the connection of the tube at its other end 53, supports the fluid tube in its co-axial relationship with the draught tube 11. The bushing 54 has an inner outwardly flared surface 55 connecting the end of the tube 52 to the inner surface of the draught tube 11 for the purpose of eliminating pockets

between the different sized fluid passageways defined by the draft tube 11 and the fluid tube 52.

The inner bore of the coupling sleeve 29 adjacent the end 53 of the fluid tube 52 is arranged to slidely receive a portion of the tubular shank 56 of a valve assembly 57. Adjacent the sliding bore, is a bore 58 of increased diameter sufficiently large to retain a coil spring 59 which embraces the tubular valve end 56.

As best shown in Figure 4, the valve assembly 57 comprises a head 60 of circular cross section having at one end a recess for receiving therein the reduced end portion 61 of a rubber valve member 62. The outwardly extending end of the rubber valve 62 is rounded for the purpose of seating against an edge of the seat 37 defined between the differently sized chambers 36 and 38.

The opposite end of the head 60 terminates in the tubular portion 56. Portions of the head 60, adjacent the tubular portion 56, are cut out to provide orifices 63 and 64 which communicate with the interior of the tubular end 56, thereby providing a fluid flow passageway from the fluid tube 52 into the chamber 38. The tubular end 56 has a shoulder 65 formed at its connection with the valve head 60 to provide an abutment for one end of the coil spring 59 whose other end seats at the end of the enlarged bore 58 in the sleeve 29.

The valve 62 has been described as being of rubber. It is to be understood, however, that the use of any other suitable material for the purpose of seating on the seat 37 is within the scope of this invention. The rubber valve 62 is maintained in its seated engagement within the head 60 by means of a flanged shaft. The rubber valve 62 has a central aperture into which partially extends a bearing bushing 66 having an outwardly extending flange 67 at one end thereof for abutment against the outer end of the rubber valve. A shaft 68 is formed to provide a flange 69 adjacent an end thereof. The extremity of the shaft is threaded as at 70 for engagement within a second recess formed at the bottom of the head recess which seats the reduced end 61 of the rubber valve. The second recess is provided with threads into which the threaded end of the shaft 68 is inserted and when so connected the shaft flange 69 abuts against the flange 67 of the bearing bushing 66.

At the other end of the shaft 68, there is provided a guide portion 71, the outer end 72 of which is preferably formed integral with the shaft and is of increased diameter. The shaft, immediately adjacent the outer end portion 72, is of increased diameter as at 68a to receive an embracing sleeve 73 which is pressed thereon after being passed over the flange portion 69 for assembly. This sleeve is of the same diameter as the outer end 72 and is preferably formed of brass or other similar and softer material. The end 72 and the sleeve 73 together form a guide which slides within the guide cylinder 39. The guide 71 together with the tubular end portion 56 guides and axially supports the rubber valve 62 in its movement toward and away from the valve seat 37. It is to be noted that the diameter of the valve chamber 38 is larger than that of the valve head 60 to permit fluid to flow thereby into and through the spigot 41 when the valve is moved away from its seat 37.

When the handle 44 is in a vertical position as illustrated in Figure 1, the valve assembly 57 is in a position in which the rubber valve 62 is seated

against the seat 37 to close the faucet against fluid flow. By rocking the handle to the right or in a clockwise direction about its pivot 46, the end portion 72 of the shaft 68 slides along the guide cylinder 39 by reason of its cam engagement with the corner 45a at the end of the handle between the cam surfaces 47 and 48. As long as this cam engagement is between the corner 45a and the shaft end portion 72, the pressure of the coil spring 59 will be sufficient to rock the handle 44 back to its normal or vertical closed position by reason of the handle corner lying below the pivot 46. However, if the cam corner 45a is operated above the end portion 72 so that the latter engages against the cam surface 47, then a release of the handle 44 will not effect a return of the handle to its vertical position. The angularity of this cam engagement, as shown in Figure 2, is such that compression of the coil spring 59 tends to urge the edge cam surface 48 into engagement with the inner or off-set surface 49 of the web 42. In other words, compression of the coil spring 59 will automatically rock the handle back to its vertical or closed position providing the handle is not rocked to a position in which the cam corner lies above the upper edge of the outer end 72 of the shaft 68. When the cam corner is rocked above the outer end 72 of the shaft, compression of the coil spring 59 will maintain the handle 44 in a position in which the nozzle is open for fluid flow through the spigot 41.

In view of the cam action between the end of the handle 44 and the outer end 72 of the shaft 68, the reason for providing the end 72 as an integral portion of the shaft becomes obvious and is for the purpose of reducing to a minimum any wear occasioned by the constant sliding cam engagement between the parts. The sleeve 73 is formed of brass or other suitable and softer material to eliminate the possibility of scoring the guide cylinder 39.

Inasmuch as a carbonated beverage, such as beer, is confined in a barrel under pressure, the beverage will flow upwardly through the draught tube 11, the fluid tube 52, the tubular end 56 of the valve, and into the chamber 38. The beverage remains trapped within the chamber 38 until the handle 44 is actuated to force the valve 62 away from its seat 37. When the valve is opened, the beverage flows through the nozzle 41 into a glass, stein, or other beverage container. As shown in Figure 2, it will be noted that the volume of trapped beverage within the fluid tube 52, the tubular end 56 of the valve structure, and the chamber 38 is very small. By actual measurement this volume of fluid has been found to be 8 cc. and is the amount of fluid which would normally be exposed to room temperatures when the faucet stands idle. Any fluid trapped within the draught tube 11 below the fluid tube 52, will naturally be exposed to the refrigeration of the box 12. In addition, the trapped beverage within the fluid tube 52 is exposed to refrigerated air which circulates upwardly through the shell 14 and into the space between the fluid tube and the draught tube by means of the openings 22a. Consequently, only a very small portion of the trapped beverage is actually exposed to room temperatures and is the volume trapped within the tubular end 56 of the valve and the chamber 38. If the faucet device were allowed to stand for any length of time, the temperature of the trapped beverage within the tube 56 and chamber 38 would materially increase. As soon as the han-

dle 44 is moved to a position in which fluid or beverage is drawn through the nozzle, the cooled fluid within the draught tube 11 immediately chills the valve tube 56 and the adjacent valve and nozzle structures. As this very small volume would be but a small portion of a glass of beverage, it is obvious that the temperature of the entire glass of beverage would vary but very little from the room temperature of the beverage contained in the cooled draught tube 11. Furthermore, the volume of trapped fluid exposed to room temperatures is so small that the amount of free carbon dioxide gas liberated as the temperature of the trapped liquid increases would be so small that the usual spitting or sudden bursts of liquid as the nozzle is opened would be entirely lacking. By reducing the amount of free carbon dioxide gas, the objection to excess foaming in drawing beverage through the faucet is entirely eliminated.

The provision of insulation within the shell surrounding the upper portion of the draught tube retards the absorption of heat by the trapped fluid within the fluid tube, the tubular end of the valve structure and the chamber 38.

From the foregoing description, it will be observed that a beverage dispensing device has been provided herein which is simple in construction, requires no refrigeration of the faucet and which automatically maintains the temperature and carbonation even of a first glass of beverage drawn after the faucet has been allowed to stand exposed to room temperatures for long periods of time. In fact, actual tests have been made in which the carbonation and temperature of a first glass of beer was found to be substantially the same after the device had stood unused for a period of twenty hours.

While a particular embodiment only of this invention has been illustrated, it will, of course, be understood that the invention would not be limited thereto, since many modifications may be made and, therefore, it is contemplated by the appended claims to cover all such modifications as fall within the true spirit and scope of the present invention.

What is claimed is:

1. In a fluid faucet, a union nozzle assembly having male and female portions, said female portion comprising a hollow coupling sleeve, an outwardly extending peripheral flange adjacent one end of said sleeve, a slot in said flange, concentric bores in said sleeve, and a coupling nut embracing said sleeve and having an inwardly extending flange at one end for abutment against said sleeve flange and interior threads at its other end, said male portion comprising a hollow T-shaped spigot, a valve chamber at one end of said spigot, a reduced bore adjacent thereto defining with said valve chamber a valve seat, said

reduced bore being continued in one branch in an axial direction in a guide cylinder of reduced diameter and being continued in another branch in an angular direction as an outlet, the end of 5 said spigot opposite said valve chamber having a U-shaped cross section with spaced side walls and a web portion, a cam actuator connected to and between said spaced side walls and having angular cam surfaces defining a rounded corner therebetween, exterior threads on the valve chambered end of said spigot for engagement by the interior threads of said coupling nut, a resilient washer between the ends of said coupling sleeve and spigot effecting a fluid-tight union assembly when coupled by said nut, interlocking means on said sleeve and spigot for holding them in alignment when connected together, a valve structure in said union assembly for opening and closing said outlet comprising a head in said valve chamber, a 10 recess in one end of said head, an apertured resilient valve having a portion seated within said recess and a rounded portion extending beyond said head, a sleeve in said resilient valve having a flange engaging an end thereof, a shaft having a threaded end for insertion through said sleeve and threadedly engaging said head, a flange on said shaft abutting the flange of said sleeve to hold said resilient valve on said head, an enlarged guide on the other end of said shaft terminating in a rounded end and seated for sliding movement in said guide cylinder, a tubular shank at the opposite end of said head in the concentric bores of said sleeve, orifices in said head communicating with the interior of said shank, and a coil spring in one of the concentric bores of 15 said sleeve embracing said reduced tubular shank for normally maintaining said valve against said seat, said cam actuator engaging said enlarged guide on the valve structure for moving the latter into and out of engagement with said valve seat.

2. A valve for a fluid faucet comprising a head, a recess at one end of said head, an apertured resilient valve member having a portion seated within said recess and a rounded portion extending beyond said head, a sleeve in the aperture of 20 said resilient valve member having a flange engaging the extending end thereof, a shaft having a threaded end for insertion through said sleeve and threadedly engaging said head, a flange on said shaft abutting the flange of said sleeve to hold said resilient valve member on said head, an enlarged guide on the other end of said shaft terminating in a rounded end, a reduced tubular shank at the opposite end of said head, and orifices in said head communicating with the interior of said shank.
